(57) **CLAIM**

The ornamental design for an adapter cover for a ground engaging machine implement, as shown and described.

DESCRIPTION

FIG. 1 is a front perspective view of an adapter cover for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate structure or features which form no part of the claimed design.

The dot-dash broken lines illustrate boundaries which form no part of the claimed design.

1 Claim, 4 Drawing Sheets
